UNITED STATES PATENT OFFICE.

OTTO A. KLINSMANN, OF FARGO, NORTH DAKOTA.

CASTER.

1,222,414.

Specification of Letters Patent.

Patented Apr. 10, 1917.

Application filed July 25, 1916. Serial No. 111,234.

To all whom it may concern:

Be it known that I, OTTO A. KLINSMANN, a citizen of the United States, residing at Fargo, in the county of Cass and State of North Dakota, have invented new and useful Improvements in Casters, of which the following is a specification.

This invention relates to improvements in casters for furniture and has for its chief characteristic to provide a guard or protecting member for the caster to prevent the same from abutting foreign objects when moving a piece of furniture, and thus eliminating the usual marring of furniture or other objects when the casters are allowed to contact therewith.

Another important object of this invention is to provide a device of this character which is rotatably mounted at right angles to the rotation of a caster wheel whereby the protecting member will not disfigure or scratch the furniture or building in any manner.

Another important object of this invention is to provide a device of this character having novel means for rotatably mounting the protecting member, the member being provided with a buffing material which may be readily removed from the member in case it becomes worn or broken.

Another object of this invention is to provide a device of this character which contains the desirable features of simplicity, durability and efficiency and furthermore a device which may be manufactured at a nominal cost.

Other objects of the invention will appear as the specification is read in connection with the accompanying drawings, in which:—

Figure 1 is a side elevation of my device showing the same applied to a caster, the device being shown in section.

Fig. 2 is a horizontal section taken on the line 2—2 of Fig. 1.

Fig. 3 is a detail view of the protecting member.

Fig. 4 is a modified form of protecting member showing the same applied to a caster.

Referring to the drawings in detail, 1 designates the lower end of a leg of a piece of furniture, the same being preferably hollow and having its lower end provided with a central opening 2. Extending upwardly through the opening 2 and into the leg 1

is a pintle 3, the latter being provided with a suitable locking means 4 whereby the bolt will be held within the leg as will be understood. The lower end of the pintle 3 which projects from the lower end of the leg has a reduced portion 5 to provide a shoulder 6, the bolt terminating in an enlarged head 7. Rotatably mounted upon the lower end of the pintle 3 is a yoke 8 of any desirable construction in which is mounted the caster wheel 9. Rotatably mounted upon the pintle 3 preferably at the reduced portion 5 thereof is my improved form of buffer which in this instance comprises a disk 10 of such a diameter as to have its peripheral edge disposed beyond the path of movement of the wheel 9. The disk 10 is provided at this peripheral edge with a depending annular flange 11, the latter being bent to provide an annular groove 12 through the medium of edge flanges 12' in which is mounted a band 13 of rubber, felt or the like. To prevent the disk 10 from rotating with the yoke 8, I have provided the yoke and disk 30 with annular grooves 14 and 15 which are arranged in confronting relation to each other to form a race-way for balls 16. The disk 10 is further bent upon its upper side to provide an annular groove 17 which is 35 of a greater diameter than the groove upon its under side, the same coöperating with a grooved washer 18 carried by the bolt to form a race-way for another set of balls 19. The washer 18 is mounted on the reduced 90 portion 5 of the bolt so that its upward movement upon the bolt is limited and therefore it will remain in coöperative relation with the upper side of the disk.

It will be seen from the foregoing description that I have provided a caster of suitable type with a protecting member which comprises the disk 10 and the flange 11, whereby the caster will be prevented from coming in contact with any objects in any position. It will also be seen that in providing a protecting or guard member with the band 13 of any suitable soft material, the member will be protected against marring an object or disfiguring it in any manner. In the event that a table having the protecting members of this type mounted upon the casters comes in contact with the wall or an adjacent piece of furniture and is moved along the same, the protecting member being rotatably mounted upon the caster, will rotate as the table is moved, thus pre-

venting the members from disfiguring the object and at the same time permitting free movement of the table.

Although I have described a specific means of mounting the protecting member upon the caster, I wish it to be clearly understood that any suitable means may be employed to rotatably mount the member upon a caster.

10 In Fig. 4 I have shown a slightly modified form in which the flange 11 instead of depending from the peripheral disk is bent upwardly to form a protector not only for the caster but for the leg 1, it being noted 15 that the disk is of a greater diameter than that of the leg. The flange is further provided with the band of soft material upon its outer side as in my preferred form.

It is thought from the foregoing taken in

connection with the accompanying drawings that the construction and operation of my device will be apparent to those skilled in the art without further description, and that minor changes in size, shape and minor details of construction may be made without departing from the spirit and scope of the appended claim.

What I claim is:

15 A guard member for casters or the like comprising a disk formed with a ball receiving channel to provide a bearing, and having a peripheral portion projected wholly to one side of the disk, a flange on each edge of said peripheral portion and a buffer secured between edge flanges of such peripheral portion.

In testimony whereof I affix my signature.

OTTO A. KLINSMANN.
